UNITED STATES PATENT OFFICE.

DANIEL H. HARDEN, OF BANKS, ALABAMA.

HAY-PRESS.

1,279,541.

Specification of Letters Patent. Patented Sept. 24, 1918.

Application filed April 6, 1917. Serial No. 160,234.

To all whom it may concern:

Be it known that I, DANIEL H. HARDEN, a citizen of the United States, residing at Banks, in the county of Pike, State of Alabama, have invented certain new and useful Improvements in Hay-Presses; and I do hereby declare the following to be a full, clear, and exact description of the invention, such as will enable others skilled in the art to which it appertains to make and use the same.

This invention is an improvement in presses and has particular reference to a hay baling press.

15 An object of the invention is the provision of improved means for operating the usual plunger of the press and, to this end, use is made of a rotary operating lever for successively actuating a pair of oscillatory members, one of which reciprocates the plunger in one direction while the other reciprocates the same in an opposite direction.

20 Another object is the provision of a press of this character which is simple in construction, easy to manufacture and effective in carrying out the purpose for which it is designed.

25 The inventive idea involved is capable of receiving a variety of mechanical expressions, one of which, for the purpose of illustrating the present invention, is shown in the accompanying drawing, wherein:—

30 Figure 1 is a top plan view of the press constructed in accordance with the invention.

35 Fig. 2 is a side elevation thereof.

Fig. 3 is a longitudinal section on the line 3—3 of Fig. 1.

Fig. 4 is an end elevation.

40 Referring more particularly to the accompanying drawing, the numeral 5 indicates the body portion of a press of any preferred construction having the hopper 6 mounted thereon and also having the plunger 7 there- 45 in which is reciprocated by the usual rod 8.

45 The mechanism for operating the plunger 7 is shown in what is now believed to be its preferred form and consists of a frame generally indicated by the numeral 9 and in- 50 cluding the side members 10 connected at adjacent ends to the body of the press 5, said side members being joined at their outer ends by the transverse end member 11. A vertically arranged bearing shaft 12 is 55 mounted in one of the side members 10 adjacent its outer end and carries an oscillatory

lever 13 which extends transversely of the frame and has its outer free end beveled as indicated at 14 for a purpose which will later appear. The lever 13 is horizontally ar- 60 ranged and supported in this position by means of a guide arm 15 carried by a bracket 16 secured to the end member 11 adjacent the shaft 12, said arm engaging the under side of the lever 13. The plunger rod 8 is con- 65 nected to an intermediate portion of the lever 13 by means of a coupling 17 so that when said lever is operated in one direction the plunger 7 will be forced inwardly in the press 5. 70

In order to reciprocate the plunger rod 8 in the opposite direction from that in which the lever 13 actuates the same, the side member 10 opposite that which carries the shaft 12 is provided with a similar bearing shaft 75 18 upon which is pivotally mounted an oscillatory lever 19 one end of which is provided with a cam surface 20. The under side of the plunger rod 8 is provided with a pair of contacting pins 21 which carry spaced 80 guide plates 22 between which is disposed the other end of the lever 19 so that when said lever is positively actuated the last mentioned end thereof will contact the contact pin 21 adjacent the free end of said rod and 85 force the same in an outward direction.

The means for oscillating the levers 13 and 19 preferably comprises a vertical bearing shaft 23 carried by the side member 10 having the shaft 18 thereon, said shaft 23 90 being positioned adjacent the outer end of said side member and has rotatably mounted thereon the operating lever 24. One end of this lever may be connected to any suitable source of power, (not shown) so that a continuous rotary movement may be imparted to the same. Carried by the operating lever 24 on each side of the shaft 23 is a spindle 25 having a roller 26 mounted upon its lower end, each of said rollers being adapted to 95 contact the beveled end 14 of the lever 13 and the cam surface 20 of the lever 19 so as to oscillate said levers in the desired direction. It will be apparent from the foregoing description that as the operating lever 24 is rotated, one of the rollers 26 will contact the beveled end of the lever 13 and force the free end thereof inwardly thus projecting the plunger 7 into the body of the press. Continued rotation of the operating lever will 100 disengage the roller from the lever 13 and immediately cause the same to engage the 105 110

cam surface 20 of the lever 19 and oscillate said lever about its pivot to cause its opposite end to strike the pin 21 adjacent the outer end of the rod 8 and pull said rod outwardly after which said roller will in turn become disengaged from the lever 19. The outward movement of the rod 8 will return the lever 13 to its normal position in the path of the rollers and when the next succeeding 10 roller engages said lever 13 and forces the rod 8 inwardly, as previously described, the lever 19 will be returned to its normal position by the contacting pin 21 adjacent the outer end of said rod 8 whereupon the cam surface of said lever 19 will again be in the path of movement of said succeeding roller and thus be in a position to again be operated.

What is claimed is:—

- 20 1. A press of the character described comprising a plunger, a rod for reciprocating said plunger, a pair of oscillatory levers for reciprocating said rod in opposite directions, one of said levers being connected intermediate its ends to one end of said rod whereby the operation of the latter will transmit motion to said rod in one direction, the other lever having a cam surface, a contact pin also carried by said rod and engageable with said other lever whereby operation of the latter will reciprocate said rod in the opposite direction, and continuously rotatable means engageable successively with the first

named lever and the cam surface of the second named lever for alternately rotating the 35 same.

2. A press of the character described comprising a body, a plunger operable therein, a rod for reciprocating said plunger, a frame connected to said body and including side 40 members, a transverse end member connecting the outer ends of said side members a vertical shaft extending through adjacent ends of one of said side members and said end members, an oscillatory lever pivoted to said shaft 45 and connected intermediate its ends to one end of said rod whereby to operate the latter in opposite directions, a second vertical shaft carried by the other side member intermediate its ends, a second oscillatory lever 50 pivotally mounted upon said second shaft and having an end in engagement with said rod whereby to reciprocate the same in the other direction, and a continuously rotatable element pivotally connected to the last 55 named side member and connected to the adjacent end of said end member and successively engageable with said oscillatory levers for alternately operating the same.

In testimony whereof I affix my signature 60 in the presence of two witnesses.

DANIEL H. HARDEN.
